(57) **CLAIM**

The ornamental design for an early learning toy set, as shown and described.

DESCRIPTION

FIG. 1 is a top perspective view of an early learning toy set, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an exploded bottom perspective view showing the pen separated from the early learning toy set.

The broken lines in the drawings illustrate the portions of the early learning toy set, which form no part of the claimed design.
